Patented June 11, 1918

2 SHEETS—SHEET 2.

UNITED STATES PATENT OFFICE.

EDWARD C. KAHN, OF MILWAUKEE, WISCONSIN.

LIQUID-FUEL BURNER.

1,269,192.

Specification of Letters Patent. Patented June 11, 1918.

Application filed January 25, 1918. Serial No. 213,660.

To all whom it may concern:

- Be it known that I, EDWARD C. KAHN, a citizen of the United States, and resident of Milwaukee, in the county of Milwaukee and 5 State of Wisconsin, have invented certain new and useful Improvements in Liquid-Fuel Burners; and I do hereby declare that the following is a full, clear, and exact description thereof.
- 10 This invention relates to new and useful improvements in burners, more particularly to those which are designed for use with vaporized liquid fuel.
- 15 The primary object of this invention is to improve upon the structures illustrated in applications, Serial Nos. 171,338 and 189,511, filed respectively on May 28, 1917, and Sept. 4, 1917, by simplifying the various elements whereby to render their assemblage 20 easier and their cost of manufacture less.

It is a more particular object of this invention to provide an improved vaporizing pipe in combination with a spray nozzle which can be very readily disconnected from 25 the burner proper and cleaned of any accumulation of soot or the like.

30 A further object is to provide an arrangement for directing heat onto the vaporizing pipe without disposing the latter directly over the burner.

An additional object is to provide a simple arrangement for adjustably attaching the combined vaporizing pipe and spray nozzle to the burner proper.

35 With the foregoing objects in view and others which will become apparent as the description progresses, my invention resides in the novel features of construction, combination and arrangement of parts which 40 will be hereinafter more particularly described and claimed.

In the drawings:—

Figure 1 is a top plan view of my invention with parts broken away and in section 45 to more clearly illustrate the improvements.

Fig. 2 is a vertical central sectional view taken substantially on the plane of the line 2—2 of Fig. 1.

Fig. 3 is a detail transverse section taken 50 on the line 3—3 of Fig. 1.

Fig. 4 is a central vertical sectional view taken longitudinally through the vaporizing pipe, and

Fig. 5 is a detail horizontal section taken substantially on the plane of the line 5—5 of Fig. 2.

Certain of the parts illustrated in the present application drawings are particularly described and claimed as well as shown in the above mentioned co-pending applications, therefore the construction and operation of these parts will not be particularly gone into in this application.

By reference to the drawings it will be noted that the numeral 1 designates the mixing or expansion chamber of my improved burner, said chamber being defined by an upper circular plate or wall 2 from which depends an annular wall 3, and a circular bottom 4, to which any suitable support may be secured as at 5. The interior of the expansion chamber is divided by partition walls and a baffle plate as shown in the latter of the two applications mentioned above.

As is also the case in said co-pending application the top wall 2 is provided at its outer peripheral edge with an upwardly and outwardly inclined flange 6 to form a recess in which is seated a burner cap 7 providing with the said wall a burner head. The gas outlets between said cap and wall may be constructed as shown in either of said co-pending applications although they are, in the present invention, illustrated as in application Serial No. 189,511.

Referring now to the more novel features of the present case 8 denotes a curved vaporizing pipe having one end portion reduced in cross sectional area as at 9, said portion being disposed substantially vertical when in normal position. From Fig. 4 it will be seen that both ends of the vaporizing pipe are internally threaded to receive a reduced coupling 10 and a plug 11, the former being threaded in the large end, and the latter in the end of the reduced portion. These parts are obviously quickly and easily removable so that when necessary the vaporizing pipe may be thoroughly cleansed of any foreign matter which may have collected on its inner wall. The coupling 10 is designed to be connected with a pipe from any suitable source of fuel supply.

From Fig. 1 it will be noted that the vaporizing pipe 8 is curved only in one di-

rection, thus differentiating it from similar pipes shown in the co-pending applications above noted. In other words in plan view the pipe 8 appears to be straight and is not disposed over the burner and receives heat therefrom in a manner to be hereinafter more particularly described.

Said vaporizing pipe is held in adjusted positions with respect to the burner by the engagement of a cylindrical stud 12 projecting from the portion 9 of said pipe with a socket 13 of a boss 14, the latter being cast integrally with the top plate 2 of the burner. For holding the stud in the socket 15 a reinforced flange 15 extends from the boss 14 and an arm 16 from the portion 9 of the pipe 8, said flange and arm being retained in co-operative relationship by a screw 17 that extends through an enlarged aperture or slot 18 in the arm 16 and into a threaded opening in the flange 15. The enlarged aperture or slot 18 permits rotation of the stud within the socket to a slight degree for the purpose of adjusting either the vaporizing pipe with respect to the burner openings or the fuel discharge opening 19 with the mixing or expansion chamber inlet 20. When the proper adjustment has been made the screw 17 is tightened and a locking screw 21 threaded through the arm 16 is frictionally engaged with the flange 15 as will readily appear from Fig. 5.

The fuel discharge opening 19 is in the reduced portion 9 of the pipe 8 and alined therewith is the threaded opening 22 in a sleeve 23 that is formed integrally with said pipe 8. A valve stem 24 is threaded through the sleeve 23 and carries a valve head 25 for opening and closing the discharge outlet 19. A handle 26 is formed on the end of the stem 24 for readily manipulating the valve. By this simple construction the discharge nozzle which is usually a distinct element from the vaporizing pipe is readily and economically constructed therewith.

Ordinarily a burner of the above described character is provided with an open topped hood 27 having an upwardly and inwardly directed portion for deflecting the flame from the burner toward the center thereof. In the present invention this hood has been modified to direct a portion of the flame from the burner opening on or toward the vaporizing pipe 8. This deflection is procured by interrupting the usual annular shape of the hood at a point adjacent the pipe 8 and connecting the ends caused by the interruption with a horizontal flange or wall 28, from the inner edge of which depends an apron 29. Fig. 1 shows this apron 29 disposed inwardly of that portion of the burner openings adjacent the pipe 8 so that the flames from said openings which strike against said apron and the wall 28 will be deflected outwardly. Also forming a por-

tion of the flame deflecting means is an ar-
cuate flange 30 which extends from one end
of the wall 28 and is disposed partly
around that portion of the vaporizing pipe
which is adjacent the reduced end 9.

From the foregoing description taken in connection with the accompanying drawings it will be evident that a liquid fuel burner has been produced which is a considerable improvement over the similar burners illus- 75
trated in said co-pending applications. The new features illustrated in the present application when combined with those claimed in the other applications will provide a most efficient and economical burner. Various 80 changes may be made in the form and proportions as well as other details of structure without departing from or sacrificing any of the principles as outlined in the appended claims.

I claim:

1. In a device of the class described, a one-piece combined vaporizing tube and discharge nozzle comprising a pipe open at both ends and internally screw threaded ad- 90
jacent its opposite ends, one end portion being reduced in diameter, said reduced end portion having transversely extending alined openings, one of said openings forming a fuel discharge port, an outwardly extending internally threaded sleeve surrounding the opposite opening, a threaded valve stem disposed through said sleeve and having a valve head to control the discharge port, a closure plug screwed in the reduced end of the pipe, 100 and a coupling screwed into the opposite end of said pipe.

2. In a device of the class described, a fuel burner having a burner outlet around its peripheral edge, a vaporizing pipe disposed outwardly of the burner, means for controlling the discharge of vaporized fuel from said pipe to the burner, and a plate disposed inwardly of the portion of said burner outlet adjacent said pipe to deflect the flames outwardly toward said pipe.

3. In a device of the class described, a fuel burner having a burner outlet around its peripheral edge, a vaporizing pipe disposed outwardly of the burner, means for controlling the discharge of vaporized fuel from said pipe to the burner, a split open topped hood surrounding said burner outlet, the interruption therein being adjacent said pipe, a substantially horizontal flange connecting the ends of said hood, and an apron depending from the inner edge of said flange inwardly of said burner outlet, said flange and apron deflecting the flames outwardly toward said pipe.

4. In a device of the class described, a fuel burner having a burner outlet around its peripheral edge, a vaporizing pipe disposed outwardly of the burner, means for controlling the discharge of vaporized fuel 130

from said pipe to the burner, a split open topped hood surrounding said burner outlet, the interruption therein being adjacent said pipe, a substantially horizontal flange connecting the ends of said hood, an apron depending from the inner ends of said flange inwardly of said burner outlet, said flange and apron deflecting the flames outwardly toward said pipe, and a curved flange extending from one end of the first mentioned flange and disposed around the pipe adjacent the outlet end thereof.

5. In a device of the class described, a burner head, a vaporizing pipe therefor, and means for adjustably mounting said pipe on the burner head including a socket formed on one, a stud carried by the other and rotatable in said socket, an arm extend-

ing from the pipe, and means on the arm for engagement with the burner head.

6. In a device of the class described, a burner head, a vaporizing pipe therefor, and means for adjustably mounting said pipe on the burner head including a socketed boss formed on the burner head, a stud carried by the pipe and rotatable in said socket, a flange on the boss, an arm projected from the pipe, and means for engagement with flange and arm to retain the pipe in adjusted positions.
